UNITED STATES PATENT OFFICE.

MICHAEL HARVEY, OF BROOKLYN, NEW YORK.

CALENDAR-HOLDER FOR DISPLAY-CARDS.

1,368,257.

Specification of Letters Patent. Patented Feb. 15, 1921.

Application filed September 20, 1920. Serial No. 411,587.

To all whom it may concern:

Be it known that I, MICHAEL HARVEY, a citizen of Russia, residing in the borough of Brooklyn, county of Kings, and State of New York, have invented a new and useful Improvement in Calendar-Holders for Display-Cards, of which the following is a description.

This invention has reference to calendar holders for display cards of various kinds and, particularly, has reference to a means for holding and supporting a calendar on the back of a stiff supporting medium such as a display, advertising or ornamental card of any kind.

Among the objects of my invention may be noted the following: to provide a means by which a calendar may be supported upon a stiff card or similar medium which may be employed for display or advertising purposes, or for works of art such as paintings in water color or oil, lithographs, etc.; to provide a simple and compact calendar holder by means of which a small calendar may be secreted on the back of a stiff medium or card which may be employed for any of the purposes noted in the foregoing; to provide means by which a calendar may be carried on the back of a supporting medium and drawn out for display, observation, use and examination and returned to position to protect the calendar and disguise the characteristics of the supporting medium; to provide a calendar holder which may be quickly and readily applied to a means of support and which, when applied, may be readily and quickly drawn out for inspection and which, at other times, may be protected from injury and hidden from view.

With the above objects in view and others which will be detailed during the course of this description, my invention consists in the parts, features, elements and combinations thereof hereinafter described and claimed.

In order that my invention may be clearly understood, I have provided drawings wherein—

Figure 1 is a front elevation or top plan view of a supporting medium having a section of the latter broken away to disclose details of construction of the calendar holder and calendar, and having dotted line indications of functional positions of the calendar;

Fig. 2 is an edge elevation, looking at either the top or bottom edge of Fig. 1;

Fig. 3 is a plan view of the holder which, when properly folded, is secured to the back of the supporting medium;

Fig. 4 is a plan view of the calendar carrier; and

Fig. 5 is a plan view of the protective member.

Referring to the drawings, the numeral 1 indicates a supporting medium for the calendar holder and associated parts, and said supporting medium may have any desired shape and is adapted to receive on its face advertising or other display media, etchings, water colors, lithographing, etc., according to the purposes for which the device is produced. This supporting medium may be of stiff paper, cardboard, celluloid, light metal, or any other material which is found suitable for the objects or purposes contemplated.

The calendar holder, shown in detail in Fig. 3, consists of a sheet 2 of flexible material capable of being readily folded or manipulated so as to produce an envelop within which the members of Figs. 4 and 5 may be enfolded and held for functional purposes. To produce the envelop or holder, the sheet 2 is cut on the lines 3—3, thus producing opposite end flaps 4, which are folded over toward each other on the dotted lines 5 so as to enable the holder to encompass and hold the two members of Figs. 4 and 5, see Figs. 1 and 2. By cutting the sheet 2 on the lines 3, and folding the same on the lines 5, the body of the sheet produces a facing or cover which is exposed at the back of the supporting medium 1, presenting two wings 6, under which the lugs 7 of the calendar carrier operate and by which they are protected. When the holder 2 is folded on the lines 5, the central body portion is only slightly greater in width than the width of the calendar carrier below the lugs 7, and, when so folded, the portions along the lines 5 at the bottom of the holder,—viewing Fig. 3,—constitute opposite side guides for the movement of the calendar holder; and the inner ends of the folded portions at both top and bottom of the holder operate as stops against which the lugs 7 on the calendar carrier engage to limit both the outward and inward movement of the calendar carrier within the holder, the lugs 7 sliding

along the protecting wings 6. This will be readily understood upon reference to Fig. 2 and broken away portion of Fig. 1. Thus the calendar carrier can be drawn down or 5 outwardly for display and inspection purposes only a limited distance, and is prevented from being pushed out of the holder when being returned within the compass of the latter.

10 The calendar carrier has secured to the body portion 8 thereof, on one side, a calendar 9 or other useful or ornamental device, it being understood that my invention is not limited to the application of a calendar to 15 the carrier. In order to manipulate the calendar carrier, a ribbon or other suitable strip 10 is applied to the carrier under the calendar or to the back of the carrier, as may be found most convenient or expeditious. Thus, when the calendar carrier is in 20 place in the holder of Fig. 3, it may be drawn downwardly or outwardly, as shown in dotted lines 11, Fig. 1, for inspection, etc., it being understood that the calendar carrier 25 is placed in the holder with the calendar facing inwardly toward the supporting medium, so that, when the carrier is drawn downwardly or outwardly, the holder or other device secured to the carrier will be 30 face up for inspection. Fig. 5 shows a protecting member the body portion 12 of which is the same shape and size as the body portion 8 of the carrier, and the lugs 13 of which are of the same shape and size and 35 are disposed similarly to the lugs 7 on the carrier. This protecting member is applied to the face of the article 9 on the carrier, and said article is thus protected facially while being moved back and forth upon the 40 supporting medium 1.

The parts are assembled by placing the calendar carrier in the holder with the lugs 7 and top edge of the carrier parallel with the short upper edges of the 45 wings 6, and the side edges of the body portion of the carrier parallel with the long side edges of said wings 6, which also brings the side edges of the carrier parallel with the bottom fold lines 5 of the holder. 50 The carrier thus places the calendar or article 9 thereon face upwardly. The protecting member is then laid upon the carrier and upon the face of the calendar 9 with all its parts registering accurately with the 55 parts of the carrier. The holder is then folded on the dotted lines 5, thus causing the flaps to turn over upon the protecting member 12. The carrier and protecting member are thus enfolded in the envelop, and the entire device as thus assembled is ready to be applied to the back of the supporting medium. The device thus prepared is secured to the back of the supporting medium 1 by applying paste or glue to the exposed 60 surfaces of the flaps 4 and to the exposed 65

surface of the body portion 12 of the protecting medium lying between the two flaps; and, in securing the device to the back of the supporting medium, slight pressure may be applied so as to cause the protecting member 70 to lie between the two adjacent edges of the flaps 4, as shown at 14 in Fig. 2, or the ridge 14 may be pressed into the body of the protecting member 12 primarily, or sufficient glue or paste may be applied to the flaps and 75 protecting member to cause the three parts to adhere to the supporting medium without producing in the protecting member the longitudinal rib or raised portion 14.

The various parts thus assembled and applied to the supporting medium 1 are held in position as shown in Figs. 1 and 2, and the carrier 8 may be drawn outwardly between the body portion of the holder and the protecting member 12 by pulling upon the 80 tape 10, thus drawing the calendar 9 downwardly, as at 11 in Fig. 1, or outwardly, as at 15 in said figure. That is to say, the device may be applied to its supporting medium so as to be drawn outwardly or exposed at its bottom edge, or it may be so applied as to be drawn outwardly and exposed at its side edge, as at 15. The lugs 7, when the carrier is drawn downwardly, engage the 85 folded portion at the bottom of the holder, and, when the carrier is returned to position within the holder, the lugs 7 engage the folds at the top or opposite end of the holder. The wings 6 on the one side and the supporting 90 medium on the other protect the lugs 7, while the body of the protecting medium 12 protects the face of the calendar 9, as the latter is shifted, it being understood that the protecting medium, as well as the holder, remain stationary on the supporting medium 95 100 at all times.

Ornamental cards, as well as advertising and display cards can be produced, according to my invention as above described, and made doubly effective and useful by having 110 the calendar applied thereto, or, in place of the calendar, some other useful and desirable medium, thus enhancing the commercial value of the article as a whole, regardless of whether it is ornate or merely an advertising or display medium.

Having thus described my invention, what I claim and desire to secure by Letters Patent is:

1. In combination with a supporting 120 medium, a sheath-like holder permanently applied to the supporting medium, a carrier for a suitable article inclosed by the holder and having a tab by which to manipulate it, and a protecting medium for the 125 carrier, overlying the latter, inclosed by the holder and fixed to the supporting medium.

2. A holder for calendars or other suitable articles composed of a sheet of flat material having its body portion at opposite sides cut 130

to produce oppositely extending wings and to provide flaps adapted to overlie the body of the holder within the boundary of the wings, and a supporting medium to which 5 the flaps are permanently secured.

3. In combination with a holder sheath-like in form and provided with overlying flaps, a calendar carrier adapted to be enfolded by the holder and having two oppositely extending lugs passing through slots 10 in the holder, the lugs of the carrier co-operating with portions of the flaps whereby the movement of the carrier is limited in two opposite directions, and a supporting

medium to which the flaps are permanently 15 secured.

4. In combination with a supporting medium, a holder of sheath-like form having two overlying flaps secured to the said medium, a calendar carrier inclosed by the 20 holder, and a protecting medium applied to the face of the calendar carrier and also enfolded by the holder, and means carried by the carrier coöperating with means of the holder to limit the movement of the carrier 25 in two opposite directions relatively to the holder.

MICHAEL HARVEY.
